DESIGN FOR A PIPE

Jack Galter, Chicago, Ill.

Application February 24, 1940, Serial No. 90,483

Term of patent 3½ years

To all whom it may concern:

Be it known that I, Jack Galter, a citizen of the United States of America, residing at 711 West Lake Street, Chicago, Illinois, have invented a new, original, and ornamental Design for a Pipe, of which the following is a specification, reference being had to the accompanying drawing, forming a part thereof.

Fig. 1 is a side elevational view; Fig. 2 is a top plan view; Fig. 3 is a bottom plan view and Fig. 4 is an end elevational view of a pipe embodying my new design.

I claim:

The ornamental design for a pipe, substantially as shown.

JACK GALTER.
